CLAIM

I claim the ornamental design of a cut stone, as shown and described.

DESCRIPTION

FIG. 1 is a front, perspective view of a first embodiment of a cut stone showing a 12×12 chaton rose having a girdle with a lower portion thereof conically chamfered of my new design;

FIG. 2 is a bottom plan view of the first embodiment of the cut stone of FIG. 1;

FIG. 3 is a front, elevational view of the cut stone of FIG. 1, the rear side elevational view being the same; and, FIG. 4 is a top plan view of the cut stone of FIG. 1.
